STRUCTURAL UNITS FOR UPHOLSTERY PURPOSES

Dagobert Meyerhardt, Opladener Str. 127, Solingen-Landwehr, Germany; Ruth Erika Gertraud Schaller, administratrix of said Dagobert Meyerhardt, deceased

Filed Dec. 16, 1955, Ser. No. 553,496

Claims priority, application Germany Dec. 21, 1954

3 Claims. (Cl. 155—179)

This invention relates to structural units for upholstery purposes and to upholstered articles produced therefrom.

In the present specification, the term "upholstered article" is used to designate cushions, mattresses, upholstered chairs, sofas, couches, divans, lounges, settees, love seats, hassocks, automobile seats, airplane seats and the like.

Heretofore, it has been common practice to use metallic springs in the manufacture of upholstered articles. These springs are usually mounted in wooden or metallic frames and covered by a layer of stuffing. Because of the rather complicated construction of the conventional upholstered articles, the manufacture of the same requires a great many different materials and tools and involves a series of rather time-consuming operations.

It is an object of the present invention to provide a structural unit for upholstery purposes, the manufacture of which does not require a great many materials. Another object is to provide an upholstery unit which can easily be put together. A further object is to provide upholstery units which make it possible to manufacture upholstered articles in a simple and economical manner. Further objects will appear hereinafter.

It has now been found that a plurality of compartments filled with air and formed by an elastic material, at least part of said elastic material consisting of an elastic foam, constitutes a new upholstery principle. Thus, the present invention provides structural units for upholstery which comprise at least two series of pieces of elastic material, the pieces of each series being spaced from one another and angularly interlocked with the pieces of the other series so as to form the partitions of a plurality of compartments, and at least one plate of elastic material forming the bottom and the top of said compartments, at least part of said elastic material consisting of an elastic foam.

In a preferred embodiment of the invention, two series of spaced pieces of elastic foamed material are interlocked at right angles so as to form the partitions of a plurality of adjoining cubic compartments, the bottom and the top of said cubic compartments being formed by at least one plate of elastic foamed material.

The invention will be specifically described with reference to the drawings, but it is understood that the invention is not limited by the physical limitations of the upholstery units illustrated and is capable of being embodied in upholstery units of other modifications than those chosen for the purpose of illustration.

Figure 1 shows a preferred embodiment of an upholstery unit constructed in accordance with the present invention. This unit comprises the interlocked pieces 1 of elastic foamed material forming the adjoining cubic compartments 2, and the plates 3 and 5 of elastic foamed material meeting at the seam 4 and forming the bottom and the top of the compartments 2.

Figure 2 is a longitudinal sectional view of an upholstery unit in accordance with the invention, wherein the bottom and the top are formed by the plate 6.

2

Figure 3 is a cross sectional view of an upholstery unit suitable for making round upholstered articles, numerals 7 and 8 designating the inner and outer covering plates, which are made from one piece of material each.

5 The interlocked partitions represented by numeral 1 in Figure 1 are preferably of equal dimensions. When shaped as illustrated in Figure 4, they may easily be put together at right angles to form cubic compartments. In order to obtain such partitions, a piece of elastic foamed material is cut as shown by the zigzag line in Figure 5, whereby two identical parts without any left-overs are formed.

10 The top and bottom of the compartments may be made from one plate of elastic foamed material as illustrated in Figure 2. Alternatively, the top and the bottom of the compartments may be formed by two or more pieces. Where two pieces of covering plate meet, they may be connected by gluing, sewing, welding, vulcanizing or in any other suitable manner.

15 When pressure is applied to the upholstery units of the invention, as by the weight of the users of an upholstered article made therefrom, the air contained in the compartments will at first be compressed and then gradually escape through the pores of the elastic foam. As a result the upholstered article will assume its final form slowly as distinguished from all conventional upholstered articles which assume their final form rather quickly. It may, thus, be seen that in the upholstery units of the invention, the air contained in the compartments and the elasticity of the foamed building material coact to bring about an ideal springiness. An upholstered article made from the upholstery units of the invention will have a high resilience in any state of compression. The use of upholstered articles made in accordance with the invention is, therefore, particularly pleasant.

20 The partitions and the covering plates (bottom and top) of the compartments can be made of any elastic foamed material, such as rubber foam, polyvinylchloride foam and polyurethane foam. It is, of course, possible to combine different types of foam in one upholstery unit. Thus, the partitions can be made of rubber foam and the covering plate of polyurethane foam or vice versa. It is also possible to make only certain elements, as, for example, the partitions of elastic foamed material and the remaining elements, as, for example, the bottom and the top of a different material.

25 The density of the elastic foamed material may range from about 25 kg./m.³ to about 50 kg./m.³, densities within the range of 35 kg./m.³ to 45 kg./m.³ being preferred. Both foams with fine pores, having a diameter of between 0.1 and 0.3 mm., and foams with wide pores, having a diameter of between 0.6 and 0.9 mm., may be employed in the construction of the upholstery units of the invention. Regarding elasticity foams should have a rebound within the range of about 20-35%.

30 In the manufacture of upholstered articles in accordance with the invention, the new upholstery units are combined in any suitable manner. Depending upon the size of the article to be made, two or more units may be arranged side by side and/or one above the other. Small upholstered articles, such as cushions, may be made of one upholstery unit having the required dimensions.

35 The upholstery units of the invention offer the advantage of greatly simplifying the manufacture of upholstered articles. Since they consist of only two structural elements, i.e., partitions and covering plates, a work shop or factory engaged in the manufacture of the new upholstered articles need only a minimum of materials and tools. Another advantage resides in the fact that the upholstered articles made in accordance with

the invention do not contain metallic parts (spiral springs). They are therefore unusually light.

The following example is intended to be illustrative only. The invention is by no means limited to it.

Example

A foamed material is prepared from the following reaction mixture:

100 parts by weight of a polyester prepared by thermal condensation of 15 mols of adipic acid, 16 mols of diethylene glycol and 1 mol of trimethylol propane; OH number 60, acid number below 1,

33 parts by weight of toluylene diisocyanate,

9.5 parts by weight of the following mixture:

3 parts by weight of bis-(diethylaminoethanol)-adipate, 1.5 parts by weight of a sulfonated ricinolic acid (water content 54%),

1.5 parts by weight of the sodium salt of a sulfonated castor oil (water content 54%),

1 part by weight of water.

Stripes 4 cm. thick and 8 cm. broad are cut from that foamed block material. These stripes are then further cut in zigzag according to Figure 5. By this procedure a plurality of identical pieces is obtained which pieces can be put together to form an upholstery of any desired dimension.

Having described my invention, I claim:

1. An upholstery unit having, in combination, walls which completely enclose a cavitated interior and interlocking partitioning members dividing the said cavity into compartments having air pervious walls, at least one of said partitioning members extending across the cavity in one direction and another partitioning member extending across the cavity in an opposite direction and crossing the first said member, each of said members having a notch therein at the point of crossing, the combined depths of the two notches being substantially equal to the height of said member whereby the combined height of the partitions at the point of crossing is substantially equal to the height of the remainder of the partitions, said walls and partitioning members being formed from cut resilient solidified foam thereby having a porous structure throughout which permits passage of air therethrough.

2. An upholstery unit having, in combination, walls which completely enclose a cavitated interior and interlocking partitioning members dividing the said cavity into compartments having air pervious walls, at least one of said partitioning members extending across the cavity in one direction and another partitioning member extending across the cavity in an opposite direction and crossing the first said member, each of said members having a notch therein at the point of crossing, the combined depths of the two notches being substantially equal to the height of said member whereby the combined height of the partitions at the point of crossing is substantially equal to the height of the remainder of the partitions, the resulting compartments formed by said partitions being substantially filled with air when the upholstery unit is compressed, said walls and partitioning members being formed from cut resilient solidified foam thereby having a porous structure throughout and having a density of from about 25 kilograms per cubic meter to about 50 kilograms per cubic meter and having pores therein of from about 0.1 millimeter to about 0.9 millimeter in cross section and a rebound elasticity of from about 20% to about 35%.

3. A method for making upholstery unit comprising preparing a partition by cutting a strip of a solidified foam material into pieces by forming alternate substantially equally dimensional and equally spaced notches and intermediate protuberances in one piece while simultaneously forming spaced complementary notches and intermediate protuberances in the other piece, assembling the resulting pieces by laying one across the other with the notches in one meshing with the notches in the other, and thereafter enclosing the assembly in a solidified foam cover.
